Mission Beach, Calif.

Filed July 5, 1956, Ser. No. 596,037

2 Claims. (Cl. 239—418)

This invention relates to spraying devices, particularly spraying devices adapted to be attached to garden hose for the purpose of entraining fertilizer, insecticides, and other chemicals in the water. Included in the objects of this invention are:

First, to provide a spraying device of the aspirator type wherein a substantial negative pressure is created in the aspirator or suction tube so that chemicals to be entrained in the spray water may be withdrawn from an open container disposed several feet below the spraying device; as, for example, from a container resting on the ground to the spraying device when held in the hand of a person in standing position.

Second, to provide a spraying device of this type which incorporates means whereby the water is discharged in a fan-shaped spray and the chemical entrained therewith is evenly distributed to the lateral margins of the fan spray.

Third, to provide a spraying device of this class which permits use of an aspirator tube of relatively large diameter to permit the entraining of chemicals which may contain a large percentage of solids.

With the above and other objects in view, as may appear hereinafter, reference is directed to the accompanying drawings in which:

Figure 1 is a plan view of the spraying device;

Fig. 2 is a side view thereof showing fragmentarily the aspirator tube;

Fig. 3 is an enlarged fragmentary plan view of the spraying device, showing particularly the impinging surface;

Fig. 4 is a fragmentary sectional view thereof, taken through 4—4 of Fig. 3;

Fig. 5 is a fragmentary sectional view, taken through 5—5 of Fig. 4;

Fig. 6 is a fragmentary sectional view, similar to Fig. 4 but limited particularly to the region adjacent the aspirator port and indicating the course of the jet stream relative thereto when the mouth of the aspirator port is unnotched;

Fig. 7 is a similar fragmentary sectional view, showing the effect of the jet stream when the downstream margin of the aspirator port is notched;

Fig. 8 is a fragmentary plan view of the impingement plate corresponding to Fig. 3, showing the path of the entrained material without the use of a distributor ridge;

Fig. 9 is a similar fragmentary plan view, showing the distribution of the entrained material accomplished by use of the distributor ridge;

Fig. 10 is a fragmentary plan view of the impingement plate, showing a modified form of aspirator mouth;

Fig. 11 is a fragmentary sectional view, taken through 11—11 of Fig. 10;

Fig. 12 is a fragmentary plan view of the impingement plate, showing a further modified construction of the aspirator mouth;

Fig. 13 is a fragmentary sectional view through 13—13 of Fig. 12;

2

Fig. 14 is a fragmentary plan view of the impingement plate, showing a further modified form of the aspirator mouth; and

Fig. 15 is a fragmentary plan view of the impingement plate, showing a further modified form of the aspirator mouth.

The spraying device includes an internally screw-threaded hose attachment member 1 adapted to be screw-threaded to the end fitting of a hose. The axial end of the attachment member 1 is closed except for a coaxial forwardly extending jet nozzle 2.

A pair of integral bracket arms 3 extend forwardly from the attachment member 1. The bracket arms are joined to a supporting frame 4 having diverging side walls 5 and a semicircular extremity 6, which supports an inclined deck 7 disposed in obtuse relation to the axis of the jet nozzle 2. The corners of the deck 7 are provided with mounting holes 8 which are bordered by knife ribs 9. The deck is also provided with a central clearance aperture 10.

The structure thus far described may be a single piece die cast member.

Mounted on the deck 7 is an impingement plate 11 having at its corners downwardly extending mounting stems 12, which are adapted to be forced into the mounting holes 8 and retained by the knife ribs 9, as indicated best in Figs. 4 and 5.

The impingement plate 11 is provided with a downwardly extending tubular ripple 13 which projects downwardly through the aperture 10. The bore of the nipple 13 intersects the upper surface of the impingement plate 11 to form a port 14. The impingement plate 11 is so located relative to the jet nozzle 2 that the water issuing therefrom impinges on the plate 11 immediately downstream of the port 14 so as to spread in a fan-shaped sheet thereover.

Downstream of the port 14 the impingement plate 11 is provided with a depressed area 15 which slopes upwardly from the port and merges at its forward or downstream margin into the normal surface of the impingement plate. The port and depressed area form an aspirator mouth, for purposes which will be described in more detail hereinafter.

The upstream side of the port 14 is provided with a small V-shaped notch 16. Also, the impingement plate 11 is provided downstream of the depressed area 15 with a crescent-shaped distributor ridge 17 disposed with its convex side facing upstream. The side margins of the impingement plate 11 may be provided with upwardly extending downstream diverging side walls 18.

The nipple 13 is adapted to be connected to a suction tube 19, the lower end of which is intended to be dipped into a liquid to be entrained in the water issuing from the jet nozzle 2. This may be facilitated by use of a weight member 20 secured to the lower end of the suction tube 19. The weight member is provided with an upwardly directed tubular attachment nipple 21 to which the suction tube is attached and is provided with feet 22 so as to hold the weight member 20 clear of the bottom 60 of the container in which it may be placed.

In practice, the spraying device is attached to the end of a hose and the container, in which the lower end of the suction tube 19 is dipped, is placed on the ground, or the container may be held in one hand while the hose and spraying device is held in the other.

It is essential in the operation of the spraying device that a substantial suction pressure be maintained at the mouth of the aspirator passage provided by the nipple 13 and suction tube 19, particularly when the spraying device is held in the hand and the liquid container is placed on the ground.

It has been found that the V-shaped notch 16 placed

at the upstream side of the port 14 apparently greatly increases the suction or negative pressure in the aspirator. Without the notch the sheet of water seems to pass over the mouth of the aspirator, as indicated in Fig. 6, without deflection into the depression. The presence of the notch 16 seems to draw the sheet of water partially into the depression, as indicated in Fig. 7.

It is not certain whether the high negative pressure deflects the water downwardly, or whether the notch creates an unbalanced force of the water to cause the deflection, but in any case the negative pressure is in fact substantially higher.

The notch 16 need not be a V-shaped notch, but may be a small rectangular notch 22, as indicated in Figs. 10 through 15.

Also, while the fan-shaped or triangular depression area 15 has been found quite satisfactory, the depression may be circular, as indicated by 23 in Figs. 12 to 15. If the depressed area be circular, it has been found advantageous to have the maximum depth of the depression slightly downstream of the port 14. It is also possible to modify the configuration of the port so as to have a widened and curved exit, as indicated by 24 in Fig. 14, or a chord-shaped exit 25, as shown in Fig. 15.

The distribution ridge 17 plays an important part in thoroughly distributing the entrained liquid with the water. For example, in Fig. 8 without the use of the distributor ridge 17 there is a tendency for the entrained liquid, indicated by A, to become concentrated in the center portion of the fan-shaped stream B issuing from the impingement plate 11. By use of the distributor ridge 17 the entrained liquid is deflected laterally to the side margins of the water stream, as indicated in Fig. 9. It will be observed that the distributor ridge 17 is quite rudimentary and influences principally the underside of the sheet of liquid passing over the impingement plate 11, and does not disturb the general pattern of the water stream as a whole. As evident from Figs. 3 and 4, the ridge 17 is not only crescent-shaped in plan but is also "crowned," that is, it is highest at its center and from there it tapers or converges in height laterally toward the surface of plate 11 and toward the side walls 18.

The importance of uniform distribution of the entrained liquid is particularly obvious when the spraying device is used for the spraying of insecticides or weedicides on the leaves of plants. In such case, absence of the distributor ridge would cause the side margins of the water stream to wash off the chemical previously deposited on the leaves of the plant.

In using the spraying device for spraying fertilizer or other chemicals which are to be absorbed in the ground, the distribution of the chemicals is not so critical. Thus for the spraying device intended primarily for such use the distributor ridge may be omitted.

While particular embodiments of this invention have been shown and described, it is not intended to limit the same to the exact details of the constructions set forth, and it embraces such changes, modifications, and equivalents of the parts and their formation and arrangement as come within the purview of the appended claims.

What is claimed is:

1. A combined hand sprinkler and aspirator for irrigating and applying chemicals to plants, comprising: an irrigation nozzle arranged for attachment to a hose and having a relatively large discharge orifice; an impingement means for deflecting water issuing from said orifice into a fan-shaped stream; said impingement means including an elongated impingement and deflecting surface positioned for obtuse engagement by water issuing from said nozzle, and upstanding walls forming with said deflecting surface an upwardly open and open-ended channel, said walls diverging from said nozzle to confine the water to said deflecting surface and limit the included angle of the fan-shaped stream discharged therefrom; a depressed area in said impingement surface; means defining an aspirator passage intersecting said depression for upward flow of aspirated fluid into said water stream; and a raised transversely elongated spreader element on said impingement surface downstream of said depressed area, said spreader element having its greatest vertical height substantially midway between said side walls and converging toward said impingement surface laterally thereof toward said side walls, said spreader element functioning to laterally distribute fluid withdrawn from said aspirator passage.
2. A combined hand sprinkler and aspirator for irrigating and applying chemicals to plants, comprising: an irrigation nozzle arranged for attachment to a hose and having a relatively large discharge orifice; an impingement means for deflecting water issuing from said orifice into a fan-shaped stream; said impingement means including an elongated impingement and deflecting surface positioned for obtuse engagement by water issuing from said nozzle, and upstanding walls forming with said deflecting surface an upwardly open and open-ended channel, said walls diverging from said nozzle to confine the water to said deflecting surface and limit the included angle of the fan-shaped stream discharged therefrom; a depressed area in said impingement surface; means defining an aspirator passage intersecting said depression for upward flow of aspirated fluid into said water stream; and a crescent-shaped rib disposed downstream of said depressed area generally transverse to stream flow and with its convex side facing said depressed area, said rib tapering laterally toward said side walls, to effect lateral distribution of aspirated fluid withdrawn from said aspirator passage and depressed area.
